CLAIM

The ornamental design for a magnifier mount, as shown and described.

DESCRIPTION

FIG. 1 is an isometric view of a magnifier mount according to the present disclosure;

FIG. 2 is another isometric view of the magnifier mount shown in FIG. 1;

FIG. 3 is a front elevational view of the magnifier mount shown in FIG. 1;

FIG. 4 is a right side elevational view of the magnifier mount shown in FIG. 1;

FIG. 5 is a rear elevational view of the magnifier mount shown in FIG. 1;

FIG. 6 is a left side elevational view of the magnifier mount shown in FIG. 1;

FIG. 7 is a top plan view of the magnifier mount shown in FIG. 1;

FIG. 8 is a bottom plan view of the magnifier mount shown in FIG. 1; and,

FIG. 9 is an isometric view of the magnifier mount of FIG. 1 shown with a magnifier that forms no part of the claimed design.

The broken lines shown in the Figures are included for the purpose of illustrating environment and portions of the magnifier mount that form no part of the claimed design.
